(57) **CLAIM**

We claim the ornamental design for an image scanner, as shown and described.

DESCRIPTION

FIG. 1 is a perspective view of the image scanner embodying our new design;

FIG. 2 is a front view thereof;

FIG. 3 is a right side view thereof;

FIG. 4 is a left side view thereof;

FIG. 5 is a rear view thereof;

FIG. 6 is a top plan view thereof;

FIG. 7 is a bottom view thereof;

FIG. 8 is a reference perspective view of FIG. 1 with the camera arm folded;

FIG. 9 is a reference perspective view of FIG. 1 with the foldable table components folded;

FIG. 10 is a reference bottom perspective view of FIG. 1 showing the bottom of the camera head; and,

FIG. 11 is an enlarged reference view of FIG. 1 showing the front of the camera head as seen from the left.
